D20-32

EX

OR D 12,893

No. 12,893.

Apr. 18, 1882.

UNITED STATES PATENT OFFICE.

ELHANAN L. MOODIE, OF NEW YORK, N. Y., ASSIGNOR OF ONE-HALF TO
CHARLES H. GILLESPIE, OF SAME PLACE.

DESIGN FOR AN ADVERTISING OR ORNAMENTAL DISK OR PLATE.

SPECIFICATION forming part of Design No. 12,893, dated April 18, 1882.

Application filed March 14, 1882. Term of patent 34 years.

To all whom it may concern:

Be it known that I, ELHANAN L. MOODIE, a citizen of the United States, residing in the city and county of New York, in the State of New York, have invented and produced a new and original Design for Advertising and Ornamental Disks or Plates, of which the following is a specification, reference being had to the accompanying drawing or photographic representation, forming part thereof.

The leading feature of my design consists in an ornamental or advertising disk or plate, on the face or front of which is the representation of a human face surmounted and, so to speak, surrounded by the representation of a "poke-bonnet," so termed, as seen from the front, the representation of the human face being placed toward the lower part of the said representation of the poke-bonnet. The representation of the human face is apparent without the use of a reference-letter. The representation of the poke-bonnet is indicated by the reference-letter B. Above the representation of the face and within the circumference of that of the poke-bonnet may be placed the figure of a sun-flower or other like decoration; but this forms no essential part of my said design. The circumference of the disk or plate is substantially identical with that of the representation of the poke-bonnet, excepting that the bottom or lower end is coincident with the lower portion

of the representation of the face, and at which last-mentioned part there is placed preferably the representation of a necktie or other suitable neckwear; but this is not absolutely necessary and forms no essential part of my said design.

It will be seen that my said design presents to the eye the effect of a human face surmounted and, so to speak, surrounded by a poke-bonnet as seen from the front, the circumference of the disk or plate embracing said design having substantially the circumference of the representation of the poke-bonnet.

It is of course to be understood that the representation of the face and also the representation of the bonnet may be tinted or colored in any desired or appropriate manner.

What I claim as my invention is—

The design for an ornamental or advertising disk or plate composed of the representation of a human face surmounted and, so to speak, surrounded by the representation of a poke-bonnet as seen from the front and having its circumferential contour substantially identical with that of the said representation of the bonnet, substantially as set forth.

ELHANAN L. MOODIE.
